US0D1061880S

(12) **United States Design Patent** (10) Patent No.: **US D1,061,880 S**
(45) Date of Patent: ** Feb. 11, 2025

(54) **UNIT END CONNECTOR**

(71) Applicant: **Fisher & Paykel Healthcare Limited**,
Auckland (NZ)

(72) Inventors: **Kevin Blake Powell**, Auckland (NZ);
Mark Thomas O'Connor, Auckland (NZ);
Brent Ian Laing, Auckland (NZ);
Jason Allan Klenner, Auckland (NZ)

(73) Assignee: **Fisher & Paykel Healthcare Limited**,
Auckland (NZ)

(**) Term: **15 Years**

(21) Appl. No.: **29/925,643**

(22) Filed: **Jan. 25, 2024**

Primary Examiner — Nathan M Johnston

(74) Attorney, Agent, or Firm — VIA LLP

CLAIM

The ornamental design for a unit end connector, as shown and described.

DESCRIPTION

FIG. 1 is a rear, top, and left side perspective view of a Nasal High-flow (NHF) unit end connector embodying our new design, with portions disclaimed;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the unit end connector that form no part of the claimed design.

1 Claim, 7 Drawing Sheets
